METHOD OF TREATING TOBACCO AND
TREATED PRODUCTErnest C. Crocker, Belmont, Mass., assignor, by
mesne assignments, to Gustavus W. Dyer, Dan-
ville, Va.No Drawing. Application June 7, 1945,
Serial No. 598,203

2 Claims. (Cl. 131—17)

1

This invention provides for the protection of tobacco from infestation by various forms of insect life, to which it is subject, especially during storage and aging operations.

When tobacco is picked, the leaves are tied up in bundles and these bundles are then cured. In curing they are more or less dried out. The partially dry condition thus produced permits of easily shaking the bundles free from loose bits of stems, leaves and the like, as well as any adherent dirt or dust which may cling to them. They still contain considerable moisture, however, when they enter the market. It is therefore customary subsequently to dry all tobaccos quite thoroughly, to render them uniform in this respect, in artificial driers. Such drying brings all of the leaves to a uniform and low moisture content. But this is usually too low for proper aging of the tobacco, which is effected best when the tobacco has a uniform moisture content, of about 11 per cent by weight. Accordingly, it is the customary procedure to inject steam into and around the dried tobacco, while it is in the form of dried, shaken and cleaned bundles, spaced apart and hung upon horizontal poles, either in a closed chamber or in the open, as desired, until it acquires a moisture content of about 11 % by weight from the steam and moist atmosphere. The bundles are then taken from the poles and laid down in layers in wooden tubs or tierces, which are stored (in suitable warehouses for the aging of the tobacco), usually for a period of 2 to 4 years, to mellow it by fermentation and aging.

Although the bundles of tobacco as thus prepared are usually sterile, the subsequent long period of storage affords great opportunity for infestation by various forms of life, such as insects, moths, larvae and the like. This is due to the fact that, in various forms of such insect life, it is capable of penetrating through very small apertures in the containers, and some are specifically attracted to the tobacco leaf as a source of food or as a suitable medium for the development of their larvae, etc. Such infestation actually consumes considerable quantities of the tobacco leaf, when it occurs. But it also deteriorates the quality of much larger quantities so that it must be discarded. It further generally degrades the quality of the entire tub or tierce of tobacco, which has been thus infested, including those portions which may not be directly reached or affected, so that it has to be accorded a much lower grade than it originally had.

In both the preparation and use of tobacco it is essential to recognize that it involves hand

2

operations and personal contact closely analogous to that of food products. Accordingly, the surrounding conditions of treatment as well as the condition of the product at all times are of first consideration and importance and must be carefully observed and controlled.

By the present invention advantage is taken of the fact that after the steaming treatment above described the tobacco as a whole is in a sterile condition. It is accordingly an object to provide a treatment of the same whereby it shall remain sterile and free from subsequent infestation, conveniently and economically, with safety to the operator and user, and also with complete effectiveness upon the tobacco treated, until it is ready to be manufactured into final form for use. Other objects will appear from the following disclosure.

In general it is found that during the storage or aging of tobacco, so long as the moisture or water content is preferably maintained at about 11% by weight, the initially sterile tobacco is substantially free from infestation or mold growth. But the tub or tierces, in which it is packed and stored for purposes of aging in the wood, and under the action of the moisture within and changing atmosphere without, gradually open up minute cracks. These form primarily between the staves but also between the boards in the heads of the tubs. They are sufficient to permit the entrance of air and the escape of air and moisture, also the entrance of small insects, moths and the like which cause damage, especially in the outer layers of the tobacco which are thus exposed and dried. The thus dried portions of the tobacco are thereby rendered favorable to the penetration of the tobacco moth into this outer layer, the laying of its eggs, and the development of larvae. The moist interior tobacco appears to be quite resistant to such infestation but the outer layer of air-dry tobacco is not.

To protect this outer zone of the tobacco in each tub or tierce, therefore (which thus becomes subject to drying and infestation during aging), it is found to be sufficient to provide it with an atmosphere containing certain chemicals which are volatile and in an amount which will be effective and remain effective throughout the period of aging, collectively or severally but without being deleterious to those handling and treating the tobacco or to those using the tobacco.

In carrying out the invention in actual practice, those portions of the tobacco which during storage

age may be or become drier (than 11% moisture)

and in which there may be an opportunity for infestation by insects, are provided with a quantity of the liquid organic chemical. This is preferably an organic compound characterized by containing oxygen and chlorine. It must be effective to destroy the insects which infest tobacco in the dry condition of storage, in extremely low concentrations in the atmosphere. It must be non-toxic to those handling the product during treatment, during storage and upon taking it from storage. It must be sufficiently volatile to permeate uniformly through the atmosphere of the charge treated therewith and yet remain within the tobacco and container throughout the long periods of storage and aging—2 to 4 years—and be free from corrosion or decomposition to form corrosive by-products, with respect to the tobacco or its container. It must be readily evaporated and removed from the container and the tobacco upon being removed from storage and exposed to the open atmosphere. It must be relatively inodorous as well as non-toxic in the concentrations employed, or, more especially, in the treated product after removal from storage and airing, and as it is put into final form for use, as in cigarettes or packaging for consumer's use as pipe tobacco, or the like. After much experimentation it is now found that the chlorinated ethers, as a class, are well suited for these purposes, and more particularly chlorine substituted ethers, which have vapor pressures at 30° C., from .05 to 1.0 mm. of mercury. For example, triglycol dichloride, which has a boiling point of about 241° C., vapor pressure at 30° C. of .07 mm.; dichloro diisopropyl ether which has a boiling point of 187° C., and a vapor pressure of .70 at 30° C., and dichloro diethyl ether, having a boiling point of about 178° C. and a vapor pressure of 0.8 mm. of mercury at 30° C.

These chemical agents have been demonstrated to be completely and specifically effective against infestation of tobacco which is dried and exposed to a relatively mild concentration of their vapors. Such a concentration may be indicated by their partial vapor pressures, as from .05/760 to 1/760 or .0000658 to .0013 mol weight per mol weight equivalent of air (22 liters).

The treatment of the tobacco with this class of agents may be effected by spraying a fine mist directly upon the tobacco after its preliminary drying treatment, or it may be applied in the course of re-moistening. For example, it may be introduced into the usual moistening chambers, dissolved in the sprays of moistening water, or vaporized and interjected with the steam used in this operation. In this way an even distribution is effected, continuously and throughout the entire mass of tobacco which is subjected to the re-moistening treatment.

On the other hand, the tobacco may be re-moistened in the usual way with water or steam and then treated with the re-agent as it is packed into the tubs or tierces for aging. In so doing, the tobacco could be packed around the periphery of the tub or tierce, and then filled in the center. In this type of packing the outer layer of bundles of tobacco leaves, placed around the sides and also those on the bottom and top, would be sprayed, while those packed in the middle portion of the tub or tierce would not need to be treated. For it is found that not only does the inside portion of the pack retain its 11% moisture throughout the aging period of two to four years, but that in such lots of simply re-moistened tobacco, which have been freely attacked by insects, they penetrate

only the dried portions of the tobacco, constituting the outer three or four inches of the charge of firmly packed tobacco. It may be said, therefore, that if this outer zone is completely protected, the inner portion of the charge will be safe from infestation.

However, it is usually practiced to lay the bundles into the tubs or tierces in layers about 4 inches deep. In so doing, in accordance with the invention, the outer bundles of each layer, or the complete surface of each layer, may be sprayed. If a dilute spray or brief spraying is employed (or where a long period of aging is contemplated), each individual bundle of the tobacco leaves might be sprayed with the liquid dispersion. When such procedure has been carried out, it might be advisable to spread out and completely air the bundles, upon removing after aging, so as to permit complete vaporization and escape of residual excess reagent from each bundle of the mass.

A preferred way of applying the reagent, however, is to apply the same in a uniform spray or coating to the inside surfaces of the wooden tub or tierce, including all of the staves, the inside of the bottom and the inside of the top. This may be effected quickly and effectively with a spray gun of any usual type, followed by charging them with the tobacco bundles in the usual way, without further operation. In this way the insecticidal reagent is uniformly applied and completely surrounds the entire charge of tobacco. It is thus in proximity to the entire outer zone of tobacco, which is most subject to drying and thus becoming susceptible to insect attack, and throughout the area of the container through which the insects, to reach the tobacco, must first penetrate.

A further adaptation of the latter procedure is to apply the organic compound to the outer surface of a sheet of paper, such as parchment or other suitable sheet material, which is then inserted into the empty tub or tierce as a liner about the side walls and over the bottom (before packing), and then over the top of the tobacco, when the container is filled. In this way, also, direct application of the compound to the tobacco leaves may be avoided, and no question of removing any excess from the tobacco after aging is involved. Especially is this advantageous in case, for example, the tobacco is removed after a shorter aging period than was originally intended and provided for in the amount of chemical which was applied.

Tobacco packed and treated and stored for aging in these ways has been found to be completely protected against infestation, even though insects in their various forms and stages were prevalent and actually infested and destroyed or greatly lowered the value and grade of adjacent tubs of the same kinds and qualities of tobacco, treated and stored in the same way, but without the chemical treatment of this invention. The saving, therefore, which is thus effected by the chemical treatment, by avoiding loss of tobacco by infestation, is not only rendered certain by the present procedure and of broad significance to the tobacco industry, but of even greater importance and value in maintaining the grade and quality of all tobaccos at the high level which characterizes them when they are put into storage at the commencement of the aging treatment.

For example, in treating tubs containing 500 pounds of tobacco each, an application of 3.50

ounces of dichloro-diisopropyl ether, by spraying over the successive layers of tobacco as packed into the tub, was completely effective in protecting the entire contents of the tub from infestation for a period of 16 months. By applying 3.0 ounces of triglycol dichloride to the inner surface of the wooden tub, followed by packing it with tobacco, the contents were protected from infestation for a like period, while tobacco in tubs, similarly packed without any chemical treatment, and aged under the same conditions for the same length of time, was seriously infested by tobacco moths, larvae, etc., and the contents greatly degraded in quality. Moreover, upon removal at the end of the aging period, the treated tobacco was substantially without odor of the chemicals, either in the course of handling or subsequent use.

In general, the addition of a sufficient amount of chemical to vaporize and develop its normal partial pressure in and throughout the atmosphere of the container (for each month of storage) is quite sufficient to effect and maintain the original conditions and concentrations under normal operating conditions of wooden tubs and in the atmosphere of tobacco warehouses.

I claim:

1. In the method of treating moisture containing tobacco, the step of treating said tobacco with a liquid ether selected from the group consist-
